DESIGN FOR A HEAD FOR A WRECKING TOOL OR THE LIKE

Charles A. Pate, Lufkin, Tex.

Application January 6, 1943, Serial No. 109,209

Term of patent 14 years

To all whom it may concern:

Be it known that I, Charles A. Pate, a citizen of the United States of America, residing at Lufkin, in the county of Angelina, State of Texas, have invented a new, original, and ornamental Design for a Head for a Wrecking Tool or the like, of which the following is a specification, reference being had to the accompanying drawing, forming a part thereof, in which,

Fig. 1 is a view in side elevation showing my new tool;

Fig. 2 is a view in plan thereof; and

Fig. 3 is an end elevation of the right-hand end as shown in Figs. 1 and 2.

I claim:

The ornamental design for a head for a wrecking tool or the like, substantially as shown.

CHARLES A. PATE.
